UNITED STATES PATENT OFFICE.

BENJAMIN F. CRAMER, OF SANDPOINT, IDAHO.

PACK-FRAME.

1,150,664.

Specification of Letters Patent. Patented Aug. 17, 1915.

Application filed February 15, 1915. Serial No. 8,272.

To all whom it may concern:

Be it known that I, BENJAMIN F. CRAMER, a citizen of the United States, residing at Sandpoint, in the county of Bonner and 5 State of Idaho, have invented certain new and useful Improvements in Pack-Frames; and I do hereby declare the following to be a full, clear, and exact description of the invention, such as will enable others skilled in 10 the art to which it appertains to make and use the same.

This invention relates to pack frames or saddles and the primary object of the invention is the provision of a frame for mounting 15 upon the back of a man to facilitate the carrying of a pack.

Another object of this invention is to provide a pack frame as specified which has a pair of arcuate swivelly supported laterally 20 adjustable arms for engagement over and against a man's shoulder for supporting the frame upon his back.

A still further object of this invention is to cover the frame with canvas for preventing 25 the pack from engaging the clothes or body of the man carrying the same.

With the foregoing and other objects in view this invention consists in such novel 30 features of construction, combination and arrangement of parts as will be hereinafter more fully described, illustrated in the accompanying drawings and claimed.

In describing the invention in detail reference will be had to the accompanying 35 drawing wherein like characters designate like or corresponding parts throughout the several views, and in which:—

Figure 1 is a perspective view of the improved pack frame showing a part of the 40 canvas covering therefor broken away. Fig. 2 is a fragmentary view partially in section of the pack frame showing one of the shoulder engaging arms in plan. Fig. 3 is a detail perspective view of the bracket for 45 swivelly mounting the shoulder engaging arm. Fig. 4 is a detail view showing the manner of lateral adjustment of the arm, and Fig. 5 is a view of a canvas blank which is inserted over the frame.

Referring more particularly to the drawings, 1 designates the packing as an entirety, which is composed of vertical side bars 2 and 3, which are connected by cross bars 4. The pack frame has cross bars 4 positioned 55 at the top and lower ends of the side bars 2 and 3 and it also has stay rods or sup-

porting rods 5 extending from one of the side bars to the other for strengthening and bracing the frame. The side bars 2 and 3 have secured thereto and suspended between 60 their facing sides, a short distance downwardly from their upper ends, a cross bar 6 which carries the shoulder engaging arms 7 and 8. The bar 6 has adjustably mounted thereupon brackets 9 and 10, which brackets 65 have their upper ends curved to form substantially a U-shape for encompassing the bar and also to form a transversely extending plate 11 to which is pivotally connected one side of a plate 12. The lower end of 70 the bracket 9 extends transversely from the back 13 thereof and has the other side of the bracket 12 pivotally or swivelly connected thereto as is clearly shown in Figs. 1, 2 and 3 of the drawings.

The bases 14 of the brackets 9 and 10 have angle plates 15 secured thereto. The angle plates 15 have screw threaded openings 16 formed in their vertically and downwardly extending sides which receive the screw 80 threaded shanks of bolts 17 for moving the brackets longitudinally upon the bar 6 upon the rotation of the bolt 17. The bolts 17 extend through the side bars 2 and 3 and have eyelets 18 formed upon their outer ends 85 for facilitating the manual rotation thereof. The bolts 17 are loosely mounted in the side bars 2 and 3.

The brackets 12 which are swivelly connected between the base plate 14 and the 90 transversely extending plates 11 of the brackets 9 and 10 have arcuate arms 20 secured thereto and extending forwardly therefrom and from the frame 1. The arcuate arms 20 are curved to substantially fit 95 a man's shoulder and they have oblong eyelets 21 formed upon their outer ends through which are inserted cushioning straps 22. The cushioning straps 22 are double thickness and are wound or bent upwardly and secured to the arms 20 adjacent the brackets 12 by whang strips or other suitable lacing material as is clearly shown in Figs. 1 and 2. The straps 22 have plates 24 slidably mounted thereupon. The straps 100 22 are inserted through slots formed in the plate 24. The plates 24 have ears or tongues 25 formed thereupon which are provided with transverse openings 26 which have inserted therethrough the bolts 26', which are 105 used for pivotally connecting the brackets 12 to the plates 11. The upper plate 11 has

a screw threaded opening 26^a formed therein which receives the upper screw threaded end of the bolt 26'. The plates 24 tend to hold the straps 22 out of engagement with the metallic arms 20.

In Fig. 5 of the drawings a blank of canvas is shown which is inserted over the frame 1 to prevent the pack which is attached thereto from engaging the body of the person. This canvas collar has its edges overlapped and secured by means of eyelets 27, which extend through and perforate the marginal edges of the blank 28 and it has its lower edge bent upwardly for forming a pocket as indicated at 29 in Fig. 5, which pocket receives the lower ends of the side strips 2 and 3. The blank or form 28 of canvas is also provided with a rectangular shaped opening 30 formed therein through which the arcuate arms 20 are inserted and it has slots 31 formed therein through which the eyes 18 of the bolts 17 are inserted.

When it is desired to mount the pack frame heretofore described upon a man's back, the arms 7 and 8 are adjusted laterally or longitudinally upon the bar 6 to provide for the proper width of the man's shoulders and the pack is attached to the frame in any suitable manner or position, as desired by the person carrying the same. If it is so desired a suitable strap may be inserted through the opening 31 and cross across the breast of the carrier for preventing the accidental loosing or displacement of the pack frame. The straps 22 rest upon the upper surface or side of the carrier's shoulder and against the front and rear parts of the shoulder, efficiently cushioning the pack frame and preventing galling of the person's body by the metallic arcuate arms 20.

In reducing the invention to practice certain minor features of construction, combination and arrangement of parts may necessitate alterations to which the patentee is entitled provided such alterations are comprehended within the scope of what is claimed.

50 What is claimed is:—

1. In a pack frame structure, a substantially rectangular frame having a pair of arcuate shoulder engaging arms swivelly carried thereby.
- 55 2. In a pack frame structure, a substantially rectangular frame having a pair of arcuate shoulder engaging arms carried thereby, said arms being adjustable for movement toward or from each other.

60 3. In a pack frame structure, a substantially rectangular frame having a cross bar formed therein, and a pair of arcuate shoulder engaging arms slidably carried by said bar for movement toward or from each other.

65 4. In a pack frame structure, a substantially rectangular frame, a cross bar carried by said frame, a pair of brackets slidably mounted upon said cross bar for movement toward or from each other, and a pair of arcuate shoulder engaging arms swivelly carried by said brackets.

70 5. In a pack frame structure, a substantially rectangular frame, a cross bar carried by the upper end of said frame, a pair of brackets slidably mounted upon said cross bar, depending ears formed upon said brackets, screw threaded bolts carried by said frame and engaging said depending ears for moving said brackets toward or from each other, and arcuate shoulder engaging arms carried by said brackets.

75 6. In a pack frame structure, a substantially rectangular frame having a cross piece carried thereby adjacent its upper end, brackets slidably mounted upon said cross piece, means for moving said brackets toward or from each other, arcuate shoulder engaging arms swivelly carried by said brackets, and shoulder pads detachably secured to the inner surface of said arcuate shoulder engaging arms.

80 7. In a pack frame structure, a substantially rectangular frame having a cross piece carried thereby adjacent its upper end, brackets slidably mounted upon said cross piece, means for moving said brackets toward or from each other, arcuate shoulder engaging arms swivelly carried by said brackets, and shoulder pads detachably secured to the inner surface of said arcuate shoulder engaging arms, and a canvas covering mounted upon said rectangular frame.

85 8. In a pack frame structure, a substantially rectangular frame having arcuate transversely extending shoulder engaging arms carried thereby, said arms being adjustable to or from each other, shoulder pads detachably secured to the inner sides of said arms, and a canvas covering mounted over said frame.

90 In testimony whereof I affix my signature in presence of two witnesses.

BENJAMIN F. CRAMER.
